US00D738255S

(12) **United States Design Patent**
Hortnagl

(10) **Patent No.:** **US D738,255 S**
(45) **Date of Patent:** **** Sep. 8, 2015**

(54) **BUCKLE**

(71) Applicant: **ABA Hortnagl GmbH**, Fulpmes (AT)

CA 2209200 2/1999
DE 3925548 3/1990

(72) Inventor: **Andreas Hortnagl**, Fulpmes (AT)

(Continued)

(73) Assignee: **ABA Hörtnagl GmbH**, Fulpmes (AT)

OTHER PUBLICATIONS

(**) Term: **14 Years**

Drawings from U.S. Appl. No. 14/247,600, filed Apr. 18, 2014.

(21) Appl. No.: **29/489,922**

Primary Examiner — Ralf Seifert

(22) Filed: **May 5, 2014**

(74) Attorney, Agent, or Firm — Volpe and Koenig, P.C.

(30) **Foreign Application Priority Data**

Nov. 4, 2013 (EP) 001388763-01-03

(51) **LOC (10) Cl.** **02-07**

(52) **U.S. Cl.**

USPC **D11/218**

(58) **Field of Classification Search**

USPC D11/1-2, 200-201, 206-210, 214-218;
24/163 R, 169-171, 173, 177-179, 191,
24/194-195, 197, 200, 614-616, 625, 198,
